(57) **CLAIM**

The ornamental design for a handle for surgical instruments, as shown and described.

DESCRIPTION

FIG. 1 is a top perspective view of a handle for a surgical instrument in accordance with a first preferred embodiment of my new design;

FIG. 2 is a magnified side elevational view thereof;

FIG. 3 is a top plan view thereof;

FIG. 4 a front elevational view thereof;

FIG. 5 is a top perspective view of a handle for a surgical instrument in accordance with a second preferred embodiment of my new design;

FIG. 6 is a magnified side elevational view thereof;

FIG. 7 is a top plan view thereof;

FIG. 8 a front elevational view thereof;

FIG. 9 is a top perspective view of a handle for a surgical instrument in accordance with a third preferred embodiment of my new design;

FIG. 10 is a magnified side elevational view thereof;

FIG. 11 is a top plan view thereof;

FIG. 12 a front elevational view thereof;

FIG. 13 is a top perspective view of a handle for a surgical instrument in accordance with a fourth preferred embodiment of my new design;

FIG. 14 is a magnified side elevational view thereof;

FIG. 15 is a top plan view thereof; and,

FIG. 16 a front elevational view thereof.
